UNITED STATES PATENT OFFICE.

JAMES FILLMORE COX, OF JERSEY CITY, NEW JERSEY.

PIPE-BENDING MACHINE.

No. 873,023.

Specification of Letters Patent.

Patented Dec. 10, 1907.

Application filed September 12, 1906. Serial No. 334,220.

To all whom it may concern:

Be it known that I, JAMES FILLMORE Cox, a citizen of the United States, and residing at Jersey City, in the county of Hudson and State of New Jersey, have invented certain new and useful Improvements in Pipe-Bending Machines, of which the following is a specification, such as will enable those skilled in the art to which it appertains to make and use the same.

The object of this invention is to provide an improved pipe bending machine which is simple in construction and operation and by means of which a pipe may be bent into segmental form without the use of an inner filling usually employed to prevent the changing of the cross sectional form of the bent portion of the pipe; and with this and other objects in view the invention consists in a machine of the class specified constructed and operating as hereinafter described and claimed.

The invention is fully disclosed in the following specification, of which the accompanying drawing forms a part, in which the separate parts of my improvement are designated by suitable reference characters in each of the views, and in which;—

Figure 1 is a front side view of my improved pipe bending machine; Fig. 2 an end view thereof looking in the direction of the arrow z of Fig. 1; Fig. 3 a partial horizontal section on the line 3—3 of Fig. 2; Fig. 4 a partial horizontal section on the line 4—4 of Fig. 1; Fig. 5 a partial vertical section on the line 5—5 of Fig. 1; and, Fig. 6 a partial vertical section on the line 6—6 of Fig. 1.

In the practice of my invention as shown in the drawing, I provide a main frame a having a top table a^2 provided at the right hand end with an extension a^3 , and said frame is provided with legs a^4 connected by transverse end members a^5 , and the extension a^3 of the table is also provided with a leg or legs a^6 , and the main frame a is provided at the front side thereof and at a predetermined distance below the table a^2 with a horizontal plate member a^7 .

Mounted vertically in the main frame is a shaft b having a support or bearing in the frame member a^7 , and said shaft passes vertically through the table a^2 , and mounted on said shaft immediately above the table a^2 is a circular bending block or wheel b^3 having an annular groove b^4 , and the shaft b above the block or wheel b^3 is threaded and provided

with a nut b^5 . In the form of construction shown, that part of the shaft b on which the wheel or block b^3 is mounted is angular in cross section as shown in Fig. 3, and the said wheel turns with said shaft, but said block or wheel may be secured to said shaft, so as to turn therewith, in any desired manner. An arm c is also connected with the shaft b so as to turn therewith, and said arm in the normal position of the parts extends forwardly from said shaft, and is provided with a longitudinal slot or opening c^2 , and mounted in said arm is a screw c^3 provided at its forward end with a transverse head c^4 having a handle c^5 by which said screw may be turned in either direction. Mounted on the screw c^3 , in the slot or opening c^2 and extending above the arm c , is a die c^6 , the face of which, adjacent to the wheel or block b^3 is provided with a horizontal groove c^7 which corresponds with the groove b^4 in the wheel or block b^3 .

Mounted on the table a^2 of the main frame and near the front edge thereof is a longitudinally movable slide d , and pivoted rearwardly of said slide as shown at d^2 is a lever d^3 which is also pivoted to the slide d at d^4 , and the connection of the slide d with the table a^2 is preferably made by means of a horizontal support d^5 which is placed on said table and with which the slide d is connected by a tongue and groove connection as shown in Fig. 2, and connected with the rear side of the slide d is a die block d^6 having a longitudinal segmental groove d^7 in its rear face, which corresponds with the grooves c^7 and b^4 in the die c^6 and the wheel or block b^3 . The die block d^6 is provided at one end with a transversely arranged arm d^8 which is secured to the end of the slide d , and said die block d^6 is also connected with the slide d by a tongue and groove joint as shown at d^9 in Fig. 2. The main frame is also provided with a longitudinal and vertically arranged hanger a^8 through which the shaft b passes, and secured to said shaft is a beveled gear wheel e , and the hanger a^8 at the right hand side of the shaft b is provided with a horizontal bearing a^9 through which is passed a shaft e^2 provided with a beveled gear wheel e^3 which meshes with the gear wheel e , and the shaft e^2 is provided at its right hand end with a worm gear wheel e^4 provided with an annular groove e^5 in which the gear teeth of said wheel are formed.

Mounted on the horizontal frame member a^7 near the right hand end thereof is a slide

arm f provided at its right hand end with an upwardly directed finger member f^2 having a pin f^3 which extends in the direction of the shaft b , and said arm is provided at its left hand end with an angular member f^4 with which is connected a crank f^5 which is pivoted to the frame member a^7 at f^6 , and which is provided with a finger f^7 which extends in the direction of the shaft b , and connected with the shaft b is an arm g which is adapted to be adjusted on said shaft to any desired position, and which operates in connection with the finger f^7 of the crank f^5 . The arm g , in the form of construction shown, is provided with an opening g^8 through which the shaft b passes and said arm is also provided with parallel jaws g^9 through which is passed a bolt g^4 by means of which the arm may be securely clamped on said shaft, but said arm may be connected with said shaft in any desired way.

The main frame a is provided near the right hand end thereof with a vertically arranged hanger support h , and secured to the lower end thereof is a plate h^2 with which is connected a vertically movable slide h^3 , the connection between the slide h^3 and the plate h^2 being a tongue and groove connection, and connected with the vertically movable slide h^3 , also by means of a tongue and groove construction is a forwardly and backwardly movable support h^4 which is pivoted at its rear end to the plate h^2 as shown at h^5 , and said support h^4 is adapted to swing in a vertical plane.

The support h^4 carries a horizontally arranged worm shaft i which ranges forwardly and backwardly of the machine, and is provided at its rear end with a belt or power wheel i^2 on which is placed a belt i^3 which is driven from any suitable source of power or power mechanism. Placed at the right hand end of the arm f and the upwardly directed finger or member f^2 thereof is a spring j which serves to force said arm to the left, and arranged horizontally in the bottom of the main frame is a shaft or rod k to which is pivoted a pedal lever k^2 to the rear end of which is pivoted a rod k^3 the upper end of which is pivoted to the support h^4 at k^4 .

In the normal position of the separate parts of this machine, the pin f^3 projects through the support h and through the plate h^2 and slide h^3 into the support h^4 , and said support is held so that the shaft i will gear with the wheel e^4 . If now the shaft b be turned, the arm g will operate in connection with the finger f^7 of the crank f^5 and force the arm f to the right. In this operation the pin f^3 will be withdrawn from the vertically movable slide h^3 and the support h^4 , and said support will drop down as shown in Fig. 5, and the worm shaft i will be disconnected from the wheel e^4 , and the movement of the shaft b will be stopped. When it is desired to start the

shaft b , the pedal lever k^2 is operated to raise the support h^4 and the pin f^3 is automatically forced into the position shown in Fig. 4, and the shaft i is thrown into gear with the wheel e^4 .

In Fig. 3, I have shown at m a pipe to be bent, and this pipe is placed longitudinally of the table a^2 , and in the groove d^7 of the die block d^6 and the end of said pipe to be connected is inserted between the die c^6 and the wheel or block b^3 . A mandrel n is also inserted into the pipe m so that the inner end thereof will be approximately in line with the longitudinal center of the arm c as shown in Fig. 3, and the screw c^3 is turned so as to force the die c^6 against the end of the pipe m and clamp the same between said die and wheel or block b^3 . The pedal lever k^2 is now operated so as to raise the support h^4 of the shaft i and throw said shaft into gear with the wheel e^4 , and the vertically arranged shaft b is turned. The extent of the rotation of the shaft b will depend on the position of the arm g , and the position of the arm g will depend upon the length of the bend which it is desired to give to the end of the pipe, and when said arm g strikes the finger f^7 of the crank f^5 the slide or arm f^4 will be forced to the right against the operation of the spring j and the pin f^3 will be disconnected from the support h^4 , and said support will drop down and disconnect the shaft i from the wheel e^4 . It will therefore be seen that the operation of the rotation of the shaft b is automatically stopped at each turn by the arm g , and the parts in connection with which said arm operates, and the machine is thrown into operation and the shaft b turned by means of the pedal lever k^2 .

In the operation of this machine, the bending wheel or block b^3 and the arm c turn with the shaft b , and the die c^6 securely holds the pipe which is drawn from the mandrel m and turns with the wheel or block b^3 as indicated by the dotted lines o in Fig. 3, and the end of the mandrel supports, the pipe at the bending point thereof, and thus prevents the shrinking of the sides of the pipe, or a change in the transverse form thereof, the bending portion of the pipe retaining at all times its circular form in transverse section. In this way a pipe may be bent at its end, or at any point of its length into segmental or circular form, the radius of the bending being determined by the diameter of the block or wheel b^3 .

Although, I have shown and described particular means for driving my improved pipe bending machine, or for turning the shaft b and for throwing said shaft into and out of operation, it will be apparent that the changes in and modifications of the means herein shown and described for driving the shaft b and for throwing said shaft into and out of operation, may be made without de-

parting from the spirit of my invention or sacrificing its advantages, and I reserve the right to make all such alterations in and modifications of these features of the construction herein shown and described as fairly come within the scope of the invention.

Having fully described my invention, what I claim as new and desire to secure by Letters Patent, is:—

- 10 1. In a machine of the class described the combination with a bending former and a vertically arranged shaft for actuating said former of a horizontally arranged shaft provided in connection with the vertically arranged shaft and provided with a worm gear wheel, a support pivoted adjacent to the worm gear wheel, a worm shaft mounted in said support, and means for operating said support so as to throw the worm shaft into and out of connection with the worm gear wheel, substantially as shown and described.
- 15 2. In a machine of the class described the combination with a bending former and a vertically arranged shaft for actuating said former of a horizontally arranged shaft provided with a worm gear wheel, a movable support mounted adjacent to the worm gear wheel, a worm shaft mounted in said support and adapted to operate in connection with the worm gear wheel, devices in operative connection with the vertically arranged shaft
- 20 and with said support for automatically throwing the worm shaft out of connection with the worm gear, and a pedal lever in connection with said support and whereby the worm shaft may be thrown back into connection with the worm gear wheel, substantially as shown and described.
- 25 3. In a machine of the class described the combination with a bending former and a vertically arranged shaft for actuating said former of a horizontally arranged shaft provided with a worm gear wheel, a movable support mounted adjacent to the worm gear wheel, a worm shaft mounted in said support and adapted to operate in connection with the worm gear wheel, and devices in opera-

tive connection with the vertically arranged shaft and with said support for automatically throwing the worm shaft out of connection with the worm gear, substantially as shown and described.

35

3. In a machine of the class described the combination with a bending former and a vertically arranged shaft for actuating said former of a horizontally arranged shaft provided with a worm gear wheel, a movable support mounted adjacent to the worm gear wheel, a worm shaft mounted in said support and adapted to operate in connection with the worm gear wheel, devices in operative connection with the vertically arranged shaft and with said support for automatically throwing the worm shaft out of connection with the worm gear, and a pedal lever in connection with said support and whereby the worm shaft may be thrown back into connection with the worm gear wheel, substantially as shown and described.

In testimony that I claim the foregoing as my invention I have signed my name in presence of the subscribing witnesses this 10th day of September, 1906.

JAMES FILLMORE COX.
